UNITED STATES PATENT OFFICE

2,030,612

AIR SEPARATOR

Thomas J. Sturtevant, Wellesley, Mass., assignor
to Sturtevant Mill Company, Boston, Mass., a
corporation of Massachusetts

Application May 3, 1934, Serial No. 723,749

12 Claims. (Cl. 209—139)

This invention relates to air separators of the whirlwind type for sizing or grading material, the general principles of which are well known in this art. As disclosed in prior United States 5 patents, for example, T. J. Sturtevant No. 1,769,721 dated July 1, 1930, a separating chamber and a surrounding collecting chamber are in communication through upper and lower openings, a fan above the upper opening causing the air to circulate upwardly through the separating chamber and downwardly through the collecting chamber in a closed circuit. The material to be graded is introduced into the separating chamber and centrifugally into the path of the rising air 10 current. The fines, or that part of the material that can be lifted and flow through rejective means located between the zone of distribution and the upper or outlet opening of the separating chamber, pass to the collecting chamber to be delivered through an outer cone to a fine outlet while the tailings, or heavier particles, gravitate downward past the lower or inlet opening of the separating chamber and are delivered through an inner cone to a tailings outlet.

20 The principal object of this invention is to increase the efficiency and to improve the selective action of the separator or to provide for varying the size of the finished product through a wide range. To this end a feature of the invention 25 comprises a powerful centrifugal rejector fan or deflector, located just under the outlet opening of the separating chamber and lying across the stream of air passing to said opening, having provision for adjustment to vary the rejective and deflective effect of its moving blades.

30 The range or flexibility of the separator may be widened by a judicious variation in the lateral position of the blades of the circulating fan in combination with the adjustable rejector fan at 35 the under side of the outlet through which the circulating fans draws the air stream for recirculation.

It has been found that a certain amount of 40 dust returns with the air that enters the separating chamber through the inlet opening. This dust should move upward with the air and not drop downward to mingle with the tailings. If a strong whirl of the air is permitted in the zone 45 above the inlet opening, there is a tendency to make a centrifugal collector of the tailings cone so that any fine dust which may re-enter the separating chamber does not return upward with the returned air, as it should, to pass again to the collecting chamber.

50 A further object of the invention is to control,

more or less, the whirl of the air within the separating chamber below the zone of distribution of the material to be graded, this is, below the distributor plate and above the inlet opening. To this end, in the preferred form of the invention, such ribs or projections as would give fanning action to the distributor plate are eliminated as far as possible, and its diameter may efficiently be less than that of its baffle plate which screens the outlet opening. The variable whirl-producing 5 rejector fan preferably is extended well across the classifying zone of the separating chamber so that, when acting in combination with a distributor plate constructed to impart a minimum air disturbance as it rotates, there will be a 10 maximum centrifugal action in the zone below the outlet opening and a minimum centrifugal action in the zone above the inlet opening, a condition which favors efficient action of the separator as a whole.

20 Further refinements and improvements relate to special forms of blade for the rejector fan, and to special forms of support for the circular series of blades composing the fan.

To the accomplishment of these objects and 25 such others as may hereinafter appear, as will readily be understood by those skilled in the art, the invention comprises the features and combinations of parts hereinafter described in detail and then pointed out in their true scope in the 30 appended claims.

The nature and scope of the invention will be 35 understood from a description of the preferred embodiment and modifications thereof illustrated in the accompanying drawings, in which:

Figure 1 is a view, in vertical section, through 40 an air separator of the whirlwind type provided with the preferred form of the improved features herein claimed;

Fig. 2 is a view, in plan, of the centrifugal rejector fan as indicated by the line 2—2 of Fig. 1;

Figs. 3 and 4 are views, in plan and in end elevation respectively, of one of the adjustable fan blades of the rejector fan shown in Fig. 1;

Fig. 5 is a view, in perspective, of the said 45 fan blade;

Fig. 6 is a view, in plan, of a modified form of the centrifugal rejector fan providing for a change in diameter;

Fig. 7 is a view showing a fragment of the edge 50 of the structure shown in Fig. 6 at the lap joint of the removable fan-bearing annulus;

Fig. 8 is a view, in plan, of the structure shown in Fig. 6 with the annulus removed and the fan blades remounted on the baffle plate;

Fig. 9 is a view showing a fragment of the edge of the structure shown in Fig. 8 at the lap joint of the baffle segments;

Figs. 10 and 11 are fragmentary views, in sectional elevation, showing the relation of the fan blades, of the two rejector fan structures shown in Figs. 6 and 8, to the cover plate of the separating chamber;

Fig. 12 is a view in perspective of a modified rejector fan blade; and

Figs. 13 and 14 are views, in section, on the lines 13—13 and 14—14 respectively of Fig. 6.

Referring more particularly to Fig. 1 of the drawings, the whirlwind type of separator therein shown comprises an outer casing 1 consisting of a drum having a cylindrical wall 3 closed by a flat head 5, and having a cone 7 at the lower end thereof terminating in a discharge spout 9. Within and spaced from the outer casing is an inner casing or drum 11 consisting of a cylindrical wall 13 covered by a flat head 15 with a centralized outlet opening 17 therein, and having a conical shell 19 at the lower end thereof. This inner casing is supported by brackets 21 between and secured to the walls 3 and 13.

Beneath and spaced from the conical shell 19 is a cone 23 provided with a discharge spout 25 which extends laterally through an opening in the cone 7 of the outer casing. The cone 23 is supported by plate struts 27 between and secured to it and the cone 7.

The inner casing forms the separating chamber 30, and the annular space between the inner and outer casing walls 3 and 13 forms the settling or collecting chamber 32. The space between the conical shell 19 and the cone 23 serves as an inlet opening for the passage of air from the settling chamber back into the separating chamber. Located at this inlet is a series of adjustable vanes 33 pivotally connected to a ring 34 secured to and projecting outward from the lower edge of the conical shell 19 and adjusted by a hand wheel all substantially as shown and described in United States patent to T. J. Sturtevant No. 1,788,361, January 6, 1931.

The materials to be graded are delivered to the separating chamber through an inclined delivery chute 35 and through a conical feed hopper 36 depending from the head 5 and having a lower cylindrical neck 37 extending down centrally through the circular outlet opening in the head 5 of the separating chamber.

Mounted on the head of the outer casing are a pair of channels 38 supporting a housing 40 which extends downward through the casing head 5 into the hopper 36 and has bearings at the upper and lower ends thereof. A vertical driven shaft 41 is journaled in said bearings and, within the portion of the housing above the head 5, has a bevel gear 42 fast thereon meshing with a bevel pinion 43 on a horizontal driving shaft 44 journaled in an inner bearing carried by the housing 40 and in an outer bearing 45 carried by a transverse channel 46 bridging the channels 38. At the outer end of the driving shaft 44 is a pulley 47 which may be driven from any suitable source of power.

The driven shaft 41 extends down from its bearing housing centrally of the feed hopper 36—37, its lower end projecting therefrom into the separating chamber 30. This lower end carries a distributor comprising a plate hub 49 and a plurality of segmental plates 50, secured to the plate hub and to each other, in a manner to provide substantially smooth faces, or so as to produce

very little air disturbance as it rotates at the lower limits of the classifying zone.

Projecting up from the margin of the distributor plate hub 49 are posts 51 carrying a cylindrical hub 52 surrounding the cylindrical neck 37 of the feed hopper and provided with a lower horizontal flange 53 and an upper cone flange 54. Secured to the cone flange 54 are a plurality of oblique arms 55 each carrying a circulating fan blade 56. The fan rotates clockwise in a chamber 60 between the casing heads 5 and 15 and its blades 56 may be radially adjusted on the supporting arms 55 by the provision of several parallel rows of bolt holes. In Fig. 1 the blades are shown as bolted on through the central one of three oblique rows of bolt holes which secures the blades in their median radial position. By bolting through the two holes of the upper row the blades will be shifted outward (see dotted lines at right of Fig. 1) and by bolting through the three holes of the lower row the blades will be shifted inward from the illustrated median position.

The distributor plate 50 is provided, as usual in this type of separator, with a circular baffle of 25 a diameter to underlie the outlet 17 and preferably located well up in the zone of selective action or classification intermediate the distributor and the outlet through the cover of the separating chamber casing. This baffle, which supports the 30 novel rejector fan blades of this invention at its upper side, may take one of several specific forms, for example, as illustrated by Figs. 2, 6 and 8.

Referring to Fig. 2 and the details of Figs. 3 to 5, the distributor baffle 65 in one embodiment 35 of the invention may conveniently be formed of six segmental sections 66 secured at their radial meeting edges in any convenient or usual manner as by flange bars 68 welded along these edges at the upper faces of the segments and punched to 40 be bolted together. The flange bars 68 are somewhat less in length than the radial dimension of the baffle leaving an uninterrupted or planate margin for mounting a marginal series of rejector fan blades 70. The planate margin of the baffle 45 is pierced by a series of regularly spaced holes 71 (Figs. 3 and 4) each adapted to receive the pivot 72 (Figs. 4 and 5) which may be a bolt passed through a blade steady or base-plate 74 conveniently in the shape of a disc which serves as 50 a turn-table and preferably is of such diameter that it will not overlap the edge of the baffle when rotatively seated in a hole 71. Each base-plate 74 supports a vertical rejector fan blade 70 secured thereto in any suitable manner as by 55 welding at the meeting joint and over the bolt head 72 which may be slotted to receive the blade if desired. The blades 70 are of greater length than the diameter of a disc 74 and preferably though not necessarily are secured with the rear 60 or inner edge thereof substantially flush with the edge of the disk. The drawings illustrate by full lines this normal setting of the blades 70 in which position they are radial and project sufficiently beyond the edge of the baffle to lap under the 65 cover plate 15 (see Figs. 1 and 5). The swivelling of the base plates on the baffle provides for setting the blades at any desired angle to the normal (full line) position (see Fig. 3), or even in a completely reversed position to bring their outer 70 edges at or within the edge of the baffle according to their relative setting on the base-plate. The base-plates may be secured to the baffle 65 for any angular adjusted position of the blades by clamps 75 bolted to the baffle plate between ad- 75

5 adjacent base-plates and long enough for their ends to overlap the base-plates. Considering the rejector fan as having a clockwise direction of rotation a forward angle of blade adjustment is shown by the dotted lines at the left in Fig. 3 and a backward angle of rotation is shown by the dotted lines at the right in Fig. 3. This would be reversed if the direction of rotation is counter-clockwise. The advantage gained by the swiveling blade mounting will presently be described.

10 A modified form of a baffle rejector fan is illustrated by Figs. 6 and 8. Here the joined baffle segments 661 produce a circular plate of slightly smaller diameter than as shown in Fig. 2 and a 15 planate margin for supporting the rejector fan blades 701 may be provided by the addition of an annular plate removably bolted to the baffle at its outer edge. In order to facilitate removal for a reason presently to be made clear, the annular 20 plate is formed of several segmental pieces 76, edge-butted and held from buckling at the joints by upper lap plates 77 (Figs. 7 and 14). There is a considerable overlap of the segments 76 at the margins of the baffle segments 661, the flange bars 25 681 being shortened to permit this. The remaining butted edges of the segments 661 are provided with under lap plates 79 (Figs. 9 and 13) for 30 rigidity. The lap plates 77 and 79 may be bolted to one segment and welded to the other. The annulus is provided with an outer and an inner circular series of bolt holes, and the baffle is provided with a single annular series of bolt holes that 35 match with the inner series of the annulus. Bolts and nuts 80 (Fig. 10) at these matching holes removably secure the two plates together. As thus erected the baffle has substantially the same diameter as the preferred baffle 65 illustrated by Fig. 2.

Each fan blade 701 may be mounted for angular 40 adjustment on a vertical pivot, to be set in one of the outer series of bolt holes in the removable annulus, by the means illustrated in Fig. 10. As there shown the blade has a recess 82 cut in its lower edge for receiving the head of a threaded bolt 84 the shank of which passes through a hole in a base-plate 711, and the blade may be secured to the base-plate by welding as before. A nut 85 on the bolt is turned up to hold the blade at any desired angle of adjustment.

50 It will be observed that for each bolt hole in which a fan blade is seated there is a corresponding bolt hole in the margin of the baffle plate. Thus the size of the centrifugal rejector fan may be varied by taking out the bolts 80, removing the 55 annulus 76 from the segment baffle 661 and then re-securing the fan blades by their own bolts and nuts in the series of bolt holes at the planate margin of the baffle. The result of this change is shown by Figs. 8 and 11.

60 The invention is not limited to the use of flat plate fan blades. For very fine products blades of the shape and form shown in Fig. 12 may be used. Here the inner oblique end of a blade 702 is provided with a projecting flange 90 overhanging the 65 impact face and the short upper edge of the illustrated blade may also have a similar flange 92. If desired, this blade may be rectangular as in Fig. 5 and the inner end or both the top edge and inner end may be provided with flanges at the impact face. The direction of rotation is indicated by the arrow, Fig. 12. Thus the flanges tend to prevent material in contact with the blade from passing to the outlet opening.

70 In any form of the rejector fan a height of 75 blade is provided that will just sweep by the stiff-

ening ring 95 at the outer edge of the outlet opening 17. Some variation in the height of the blades may be required should the blade supporting margin of the baffle not lie in a plane parallel to that of the casing cover plate 15.

75 Those skilled in the art will recognize the advantages gained by a separator having the flexibility of construction hereinabove described. The effect of the circulating fan may be varied by shifting its blades inward or outward. The rejector fan may be varied in size and may have any number of blades desired and of any shape desired. The rejector fan blades may be set at either a forward angle to produce a coarser product or at a backward angle which causes the 15 blades to reject more material and thus produce a finer product. The radially set blades will produce a separated product of an intermediate fineness. The blades may project well toward the wall of the separating chamber or may be wholly 20 above the baffle support.

25 It will be observed that the rejector fan operates as close as is mechanically possible to the outlet of the separating chamber. For simplicity and convenience this fan is mounted on the distributor baffle although it may be a separate device. By just sweeping the under side of the cover plate surrounding the outlet there is little chance of the unseparated material passing over the fan and thus to the collecting chamber. 30 The fan blades, extending, as preferred, to sweep a circle larger than the outlet opening, keep the dust laden air in the classifying zone violently whirled and act to deflect, bat or centrifuge the oversize particles outward or to the covered corner 35 of the separating chamber where they drop down, while permitting the fines to pass through the fan and thus to the outlet to be lifted by the circulating fan. Thus centrifugal selective action is continual. As hereinbefore stated the 40 deflective or rejective action can be varied through a wide range by due selection of the inclination which these faces of the fan blades are to have with respect to a radial position.

45 The nature and scope of the present invention having been indicated and its preferred embodiments having been specifically described, what is claimed as new, is:—

1. In an air separator of the type described, the combination with a circulating fan for causing air currents to flow upward through a top outlet of a classification zone and a rotary distributor in the lower part of said zone, of a rotary rejector fan between the distributing plate and circulating fan comprising a support having 50 a circular series of rejective fan blades each of said fan blades being adjustable on a vertical axis to turn the faces of the blades at an angle forward or backward from a radius in regard to the direction of rotation thereby to vary the 55 rejective effect, and means for securing said blades in any selected position either radial or oblique to radial.

2. The air separator described by claim 1 in which each rejector fan blade is individually adjustable and is separately secured in its selected position.

3. The air separator described by claim 1 in which the support for the rejective fan blades 70 consists of an imperforate plate below and baffling said top outlet.

4. In an air separator of the type described, the combination with a covered casing defining a zone of classification and having an outlet open- 75

ing through its cover, a circulating fan for causing an air stream to flow upward within said casing and through said outlet and a rotary distributor for delivering the material to be classified into said rising air stream, of a rotary rejector fan located well above said distributor having a series of vertically set blades the upper edges of which sweep substantially in the plane of said outlet, said rejector fan blades being angularly adjustable in a horizontal plane to deflect or centrifuge material outwardly, in a varying degree, through said air stream.

5. The air separator, described by claim 4 in which said rejector fan comprises a baffle plate above the distributor having said series of fan blades mounted at its margin, each blade having a face height sufficient to extend upward from the baffle to sweep substantially in the plane of said outlet as described.

20. 6. In an air separator of the type described, the combination with a covered casing defining a zone of classification and having a centralized outlet through its cover, a circulating fan for causing an air stream to flow upward within said casing and through said outlet, a baffle plate below said outlet and means below said baffle plate for distributing material into said air stream, of a series of rejective fan blades at the margin of said baffle plate, each blade being mounted on a vertical pivot pin with its face normal to the plane of the baffle plate, and means for setting said blades in a radial or oblique to radial position as desired to regulate the size of the material to be carried in the air stream through said outlet.

35. 7. The air separator described by claim 6 in which the pivot pin is so related to the edge of the baffle and to the ends of the blade that in one radial setting the blades all project beyond the edge of the baffle plate while when turned 40 90° to a reversed radial setting the blades do not so project.

8. The air separator described by claim 6 in which each blade is secured to a steadyng plate 45 or turn-table and said pivot pin projects from

the lower face of said turn-table and seats in a hole in the baffle plate.

9. In an air separator of the type described having a rotary shaft within the separating chamber, a distributor including a baffle cover plate rotated by said shaft, and a series of rejective fan blades at the margin of said distributor cover plate, each set vertically and each angularly adjustable about a vertical axis, and means for securing said blades in any position 10 of adjustment at will.

10. In an air separator of the type described the combination with a circulating fan above the outlet of a classification chamber for causing an air stream to flow upward through said outlet and 15 means within the classifying chamber for distributing material into said air stream below said outlet, of a rejector fan intermediate said distributing means and said outlet, and means for varying the combined action of the circulating 20 and rejector fans to regulate the size of the material selected and drawn through the outlet comprising means for varying the relation of the blades of the circulating fan to the outlet and means for varying the rejective the rejective and 25 deflective action of the blades of the rejector fan on the material in the air stream attempting to pass through said rejector fan to the outlet.

11. The air separator described by claim 10 in which the circulating fan blades are adjustable 30 radially to increase or decrease the diameter of said fan and in which the rejector fan blades are adjustable angularly on a vertical axis to increase or decrease the centrifugal action on the material flowing inward through the rejector fan and im- 35 pinged by its blades.

12. A rejector fan to be positioned within the separating chamber of an air separator of the class described and in the inward path of the dust laden air comprising a baffle plate, a series 40 of blades mounted at the margin of said baffle each individually adjustable by rotation on a vertical axis to vary the outside diameter of the circle swept by said fan blades.

THOMAS J. STURTEVANT. 45
